US00D527820S

(12) **United States Design Patent** (10) **Patent No.:** **US D527,820 S**
Solar et al. (45) **Date of Patent:** ** *Sep. 5, 2006

(54) **FIDUCIAL MARKER**

(75) Inventors: **Matthew S. Solar**, Indialantic, FL (US); **Thomas L. Bridges**, Melbourne Beach, FL (US); **David M. Lee**, Melbourne Beach, FL (US); **Mark Stephen Freas**, Indialantic, FL (US); **Rudy A. Mazzocchi**, Indian Harbor Beach, FL (US)

(73) Assignee: **Image-Guided Neurologics, Inc.**, Melbourne, FL (US)

(*) Notice: This patent is subject to a terminal disclaimer.

(**) Term: **14 Years**

(21) Appl. No.: **29/199,266**

(22) Filed: **Feb. 12, 2004**

(57) **CLAIM**

The ornamental design for the fiducial marker, as shown and described.

DESCRIPTION

FIG. 1 is a perspective view of the fiducial marker, incorporating the new design.

FIG. 2 is a side elevational view of the fiducial marker of FIG. 1.

FIG. 3 is a top view of the fiducial marker of FIG. 1.

FIG. 4 is a bottom view of the fiducial marker of FIG. 1; and, FIG. 5 is a sectional view of the fiducial marker of FIG. 1, illustrating the divot shown in FIGS. 1 and 3.

The broken lines shown in the Figures are for illustrative purposes only and form no part of the claimed design.
